UNITED STATES PATENT OFFICE.

DANA H. BENJAMIN, OF CLEVELAND HEIGHTS VILLAGE, AND BLUFORD W. BROCKETT, OF CLEVELAND, OHIO, ASSIGNORS TO THE AMERICAN LAUNDRY MACHINERY COMPANY, OF CINCINNATI, OHIO, A CORPORATION OF OHIO.

CLOTHES-PRESSING APPARATUS.

1,230,984.

Specification of Letters Patent. Patented June 26, 1917.

Application filed December 1, 1915. Serial No. 64,499.

To all whom it may concern:

Be it known that we, DANA H. BENJAMIN and BLUFORD W. BROCKETT, citizens of the United States, residing at Cleveland Heights Village and Cleveland, respectively, in the county of Cuyahoga and State of Ohio, have invented certain new and useful Improvements in Clothes-Pressing Apparatus, of which the following is a specification.

10 This invention relates to improvements in clothes pressing machines and particularly to that class of such devices wherein the garments are subjected to pressure between heated members, the one engaging the right 15 side of the fabric, being provided with a pressing surface which will not mat the nap of the fabric and produce a gloss thereon.

More specifically the invention relates to an apparatus for pressing garments having 20 a nappy finish and it consists of co-operating pressing members, one of which is provided with suitable padding and the other of which is provided with a pressing surface having innumerable hardened projections 25 and intervening recesses which in the one instance extend into the fabric and in the other receive the fibers and prevent the matting thereof and therefore avoid the production 30 of a glossy finish on the seams, the material utilized being preferably emery cloth or emery paper or any similar surface having projections of a crystalline character with intervening interstices.

The invention may be further briefly summarized as consisting in the construction and combination of parts hereinafter set forth in the following description, drawings and claims.

Referring to the drawings, Figure 1 is a 40 front elevation; Fig. 2 is a section through the several bucks; Fig. 3 is a left end elevation; Fig. 4 is a detail showing the yielding means for the upper buck; Fig. 5 is a sectional view of this device; Fig. 6 is a top 45 plan view of the machine; Fig. 7 is a detail view of the equalizer for the upper buck; Fig. 8 is a bottom plan view of one of the bucks; Fig. 9 is a cross section of the same;

and Fig. 10 is an enlarged sectional view of a piece of the buck covering.

In carrying out the invention any preferred form and construction of parts may be employed so long as it possesses the necessary characteristics, but we have shown one form in the drawings which is effective, and 50 in such embodiment 1 represents a base provided with a stationary buck standard 1' having an upper platform portion 2 provided with openings adapted to receive bolts 3, one arranged near each corner and all secured rigidly within a buck support 4. These bolts receive between the platform 2 and the base of the support 4 suitable 55 springs 5. Below the platform 2 these bolts are provided with nuts 6. The support 4 is cut in from one end to form a recess 7 for receiving the portion of the garment which passes under this buck. Secured to the top of this support 4 is a lower ironing buck 8 preferably provided with a steam 60 chamber 9 to be furnished with steam from any suitable source.

To the rear of the standard 1 is a main operating shaft standard 10 and an auxiliary standard 11. These two standards are 65 provided with bearings 12 and 13 respectively. These bearings support a rock shaft 14 extending beyond both bearings, the portion extending beyond the bearing 12 being tapered at 15 and reduced and threaded at 70 16 for a purpose to be described. Mounted upon the rock shaft 14 are intermediate buck supporting brackets 17 and 18, the former being rigidly secured to the shaft just inside of the bearing 12, and the latter being 75 rigidly secured to the shaft just outside of the bearing 13. These two brackets are integral with an intermediate buck 19 provided with a steam chamber 20 to be supplied with steam from any suitable source, 80 and in any suitable manner. Loosely mounted upon the rock shaft 14 is an upper buck supporting bracket comprising side portions 21 spaced apart and each having at its outer end a shaft receiving portion 95 22, these two bearing portions receiving a

shaft 23 which passes through eyes 24 preferably formed integral with the upper buck 25. This upper buck has a steam chamber 26 therein. The shaft 23 is held within the 5 shaft receiving portions 22 by means of suitable set screws 27 holding the shaft against rotation. Secured to this shaft by set screw 28' between the inner eyes 24 is an equalizing member 28 having laterally extending 10 portions 29 provided with springs 30 engaging the upper face of the upper buck on either side of the central longitudinal axis thereof and serving to give it a definite relationship with respect to the intermediate 15 buck member.

The side portions 21 of the upper buck supporting bracket merge into one on the side of the shaft opposed to the upper buck and form a boss 31 which is slotted at 32 and receives a bolt 33. This bolt is provided with a head 34 engaging in a recess 35 formed in a block 36 provided with a flange 37 secured by bolts 38 to the upper end of a standard 39. The shank of the 20 bolt passes through an opening 40 in the block 36. The block 36 below the head of the bolt 34 is recessed at 41 to receive a tongue 42 of a bar 43 which extends to the front of the machine and is there provided 25 with a hand piece 44. Above the block 36 the shank of the bolt is provided with a nut 45 engaging a spring 46. This spring thrusts against a washer 47 engaging the underside of the boss 31 while on the upper 30 side of the boss the shank is provided with a nut 48 held in place by a check nut 49.

In order to transmit pressure from the driving mechanism to the bucks the tapered portion 15 of the shaft 14 is provided with a 40 hub 50 having a downwardly extending arm 51. This arm has at its lower end a fork 52 provided with a cam 53 on the outside of the end of each fork. The hub 50 is provided with a laterally extending arm 54 having a 45 counterweight 55 secured thereto. A suitable nut 56 holds the hub 50 in place, and the hub is fastened in any suitable manner to the tapered portion so that these parts operate the shaft.

50 Coöoperating with the cam 53 is suitable driving mechanism, and it comprises a bearing bracket 57 provided with a bearing portion 58 having a cap 59. This bearing receives a shaft 60 to which is keyed a peripheral cam 61 in extent a little greater than a semi-circle.

Assuming that the parts are in the position shown in Fig. 3, the operator moves the intermediate member upward until it is in 60 engagement with the upper buck, then places the garment upon the lower buck. He then shifts the intermediate buck until it engages upon the top of the garment and applies power through mechanism to be described, 65 causing the cam 61 to rotate in a counter-

clockwise direction, as shown in Fig. 3, and moves the arm 51 and the intermediate buck in a clockwise direction. This causes pressure to be brought to bear between the intermediate buck and the lower buck. The 70 power mechanism is then released from the shaft 60.

Any suitable mechanism may be provided for rotating the shaft 60 first in one direction then in the other, but since this mechanism constitutes no part of the invention it has not been shown or described, it being only important that when the buck 19 is moved downward the cam 61 should be rotated in counter-clockwise direction as 75 shown in Fig. 3, so that it will engage one of the cams 53 and force the buck 19 downward, the reverse rotation causing the cam 61 to coöperate with the other cam 53.

The engaging surfaces of the several 80 pressing members are equipped in the following manner. The upper surface of the lower buck 8 and the upper surface of the intermediate buck 19 are both provided with suitable padding 62 held in place by pins 90 63 and by bands 64 applied in the usual manner. The lower face of the intermediate buck 19 and the upper buck 25 are each provided with a suitable pressing surface preferably produced by applying a sheet of 95 yielding material 65 thereto comprising a support 66 having a plurality of projections 67 of crystalline character with intervening interstices or recesses 68, the material preferably utilized being either emery cloth or 100 emery paper. In each instance the buck to which this covering is applied is supplied with a bead 69, over which the covering is formed and it is then held above the bead by a clamping band preferably made in halves 105 70 and 71 which separate on both sides of the buck at some point intermediate the ends. At the point of separation each half portion of the band is provided with outwardly extending lugs 72 provided with suitable openings for receiving clamping bolts 73 having wing nuts 74 thereon. These half bands firmly clamp the material in place over the pressing surface of the buck.

In use the garments are placed upon the 115 padded surface with the right side away from the padding. The press is then closed when the projections of the covering fabric will embed themselves in the fabric and prevent in the first instance the formation of a 120 matted surface and the consequent production of a gloss, and in the second place will engage some of the fibers and pull them out thus further breaking up any matted or 125 glossy surface.

Having described our invention, we claim:—

1. A press for fabric comprising pressing members, one of said members being provided with a pressing surface consisting of 130

innumerable projections and recesses, said projections being of a crystalline character, and means for opening and closing said members.

5. 2. A press for fabric comprising pressing members, one of said members being provided with a covering of emery cloth or paper, and means for moving said members into and out of engagement.

In testimony whereof we affix our signatures in presence of two witnesses as follows:

DANA H. BENJAMIN.
BLUFORD W. BROCKETT.
